UNITED STATES PATENT OFFICE.

CHARLES HAZEN BROWN, OF BOSTON, MASSACHUSETTS.

DIE FOR UPSETTING FLANGES ON RIVETS.

SPECIFICATION forming part of Letters Patent No. 430,374, dated June 17, 1890.

Application filed January 24, 1890. Serial No. 338,001. (No model.)

To all whom it may concern:

Be it known that I, CHARLES HAZEN BROWN, of Boston, in the county of Suffolk and State of Massachusetts, have invented certain new 5 and useful Improvements in Dies for Upsetting or Flanging Rivets, of which the following is a specification.

This invention relates to the operation of upsetting rivets which are provided with solid 10 shanks having cup-pointed outer ends which are spread or turned outwardly to form a second head or flange.

The invention has for its object to provide improved means whereby the spreading or 15 outward turning of the cup-pointed end of the rivet may be effected by successive operations rapidly performed; and to these ends it consists in a flange-forming die composed of a plurality of parts, preferably two, one of 20 which comprises the central portion and the other the marginal or outer portion of the flange-forming die, the said central portion being supported by a stout spring above the acting face of the marginal portion, the arrangement being such that when the rivet is 25 pressed against the central portion the supporting-spring of the latter will hold said central portion with sufficient firmness to enable it to spread the cup-pointed end of the rivet 30 until the bottom of the recess in the rivet bears upon the acting face of the central portion, the latter then yielding until it is substantially flush with the marginal portion of 35 the die, so that the flange which is partially formed by the spreading of the cupped end of the rivet on the central portion of the die is completed by a pressure against the marginal portion of the die, the two operations following each other in rapid succession and without 40 changing the rivet from one die to another. By thus forming the second flange of the rivet in two stages or operations liability of cracking or breaking said flange during the operation is avoided, and a flange is produced 45 which presents a continuous edge free from cracks or flaws.

Of the accompanying drawings, forming a part of this specification, Figure 1 represents a side elevation of my improved die in conjunction with means for supporting it and for pressing the rivet against it. Figs. 2, 3, 50 and 4 represent sections, on a larger scale,

showing the operations of the die in forming the second flange of the rivet. Fig. 5 represents a modification, showing the die made in 55 three parts.

The same letters of reference indicate the same parts in all the figures.

In carrying out my invention, referring to Figs. 1, 2, 3, and 4, I provide a die for the 60 formation of the flange or second head on a cup-pointed rivet *d*, of substantially the form shown in Fig. 2, said die being composed of a body *i*, preferably of cylindrical form, having at one end a concave acting face *a* and 65 provided with a longitudinal bore or socket extending from said face through said body, the face being therefore of annular form, and a core or rod *j*, fitted to move lengthwise in said bore or socket and provided at its outer end with an acting face *a'*, of conical or approximately conical form. The core or rod *j* is supported with its acting face *a'* above the acting face *a* by means of a stout spring *b*, which is adapted to yield until said acting face *a'* is at 70 its marginal portion substantially flush with the inner edge of the acting face *a*, as shown in Fig. 4. The arrangement of the spring *b* may be variously modified; but I do not limit myself to any particular arrangement. I have here 75 shown the spring supported between its ends by a bearing *k*, attached to the supporting-frame *m*, which holds the body *i* of the die, one end of said spring being engaged with a groove in the lower end of the rod or core *j*, 80 while the other end bears upon a screw *o*, which is adjustable in the frame *m* and enables the tension of the spring *b* to be adjusted. *p* represents a plunger or forcer 85 which is arranged to press the rivet *d* against the core *j* and die-body *i*. Said plunger may be reciprocated by any suitable mechanism; but as the plunger and means for operating it form no part of the present invention the operating mechanism is not shown.

The rivet *d*, being inserted in the pieces of material *r r* to be united and placed between the plunger *p* and the die *i j*, as shown in Fig. 2, the cupped end of the rivet resting on the elevated face *a'* of the core *j*, the plunger is pressed downwardly until the cupped end of the rivet is spread upon the conical face *a'*, as shown in Fig. 3. The spring *b* is sufficiently stiff to support the core *j* and prevent 95 100

it from yielding while the cupped end is being thus spread; but when the solid portion of the shank of the rivet comes to a bearing on the face a' the continued pressure exerted by the plunger p through the rivet-shank causes the core j to yield until the margin of the face a' is substantially flush with the inner margin of the face a , as shown in Fig. 4, the partially-turned flange on the cupped end 10 of the rivet being then pressed against the concave face a , and therefore spread and converted into a complete second flange, as shown in Fig. 4.

It is important that the yielding movement 15 of the core j be limited, so that the margin of the face a' will not fall below the inner margin of the face a , as otherwise the said inner margin would form a shoulder projecting above the face a' , which would deface or 20 cut the outer surface of the completed flange formed by the described operation. I therefore provide a stop s at the lower end of the core or rod j , arranged to arrest the yielding movement of said core when its acting face 25 a' reaches the position shown in Fig. 4. Said stop is preferably an adjustable screw, which may be set to permit a greater or less displacement, as may be required.

It will be seen that the two operations, 30 though successive, may be performed in such quick succession that the flange-forming operation will be as rapid as if the flange were formed entirely by a die or anvil composed of one piece. I have found in practice that 35 by spreading the cupped end of the rivet by two successive operations the liability of cracking the metal of the flange thus formed is entirely obviated, and a flange is produced having a continuous or unbroken margin.

40 I do not limit myself to making the die in two sections or parts, as in some cases it may be desirable to make the die in more than two sections. Fig. 5 shows three sections--viz., the rod or cord j , the outer portion or body i , 45 and an intermediate tubular core j' , the latter

being supported by a spring b' below the acting face of the core j and above the acting face of the body i , and arranged to partially spread the end of the rivet after the initial spreading by the face a' and before the final spreading by the face a .

I claim—

1. A rivet-flange-forming die composed of an inclosing part or body, and one or more yielding cores or sections located within said body and normally projecting above the acting face thereof, as set forth. 55

2. A rivet-flange-forming die composed of an inclosing part or body having an operating face at one end, and a movable core within 60 said body, having an operating face which is normally held with a yielding pressure above the operating face of said body, as set forth.

3. The combination of the die-body having an operating face; a core or plunger movable 65 in said body and having an operating face surrounded by the operating face of said body, and a spring whereby the core is normally supported with its operating face above the operating face of the die-body, as set forth. 70

4. The combination of the die composed of the body i and the spring-supported core j , a holder for said parts, and a plunger arranged to force the rivet against said core and die-body, as set forth. 75

5. The combination of the die composed of the body i and the spring-supported core j , a holder for said parts, a plunger arranged to force the rivet against said core and die-body, and a stop to limit the yielding movement of 80 the core, as set forth.

In testimony whereof I have signed my name to this specification, in the presence of two subscribing witnesses, this 11th day of January, A. D. 1890.

CHARLES HAZEN BROWN.
